(57) **CLAIM**

The ornamental design for a lens assembly, as shown and described.

DESCRIPTION

FIG. 1 is a perspective view of a lens assembly; FIG. 2 is a top plan view of FIG. 1; FIG. 3 is a bottom plan view of FIG. 1; FIG. 4 is a right elevation view of FIG. 1, with the left, front and rear elevation views are identical; and, FIG. 5 is an exploded perspective view of FIG. 1. The broken lines shown in the drawings are for the purpose of illustrating portions of the lens assembly and form no part of the claimed design.
